RAILS

Seymour H. Raskin, 4242 Lomo Alto, Dallas, Tex.
Filed May 18, 1962, Ser. No. 195,936
6 Claims. (Cl. 238—122)

This invention relates to rails and more particularly to rails usable in vehicle weighing devices.

This application is a continuation-in-part of my co-pending application filed January 28, 1960, Serial No. 5,296, for a weighing device and method.

An object of the invention is to provide a new and improved rail for use in vehicle weighing devices which detect the deflection of the rail as a load rolls over the rail to measure the weight of the load.

Another object is to provide a rail of a type described having a tread along which a beveled wheel of a railway vehicle may roll, each point of the tread being disposed at the center of gravity of the rail of a transverse cross section thereof so that the deflection of the rail when supported at its ends will depend only upon the weight of the load imposed thereon by a wheel rolling along the tread.

Still another object is to provide a rail which is of a substantially channel shape and has a longitudinal intermediate rib extending upward from the horizontal web thereof to provide a longitudinally extending tread, and further has flanges disposed above the tread whereby the center of gravity of any cross section of the rail lies at the tread at that cross section.

Additional objects and advantages of the invention will be readily apparent from the reading of the following description of a device constructed in accordance with the invention, and reference to the accompanying drawings thereof; wherein:

FIGURE 1 is an end view of a rail embodying the invention and showing a beveled flanged wheel, such as a railway vehicle wheel, in position contacting the tread of the rail; and,

FIGURE 2 is a perspective view of the rail illustrated in FIGURE 1.

Referring now to the drawings, the rail 10 embodying the invention is substantially channel shaped, having a base or web portion 11 provided with integral vertically upwardly extending legs 12 and 13 at the sides thereof. The base 11 has a flat bottom surface 15 so that the rail may be secured at its opposite end portions to any suitable fixed supports leaving the intermediate portion of the rail free to deflect downwardly upon the imposition of a load thereon.

An elongate rib 16 integral with the base extends upwardly between the legs 12 and 13 and has an elongate tread or load bearing surface 18 which may be engaged by the beveled annular surface 19 of a railway wheel 20 as the latter rolls along the rail, thereby to support the wheel and the railway vehicle on which the wheel is mounted. The rib has an arcuate rounded edge 21 in order to provide clearance for the tapered annular surface 19 of the wheel so that the wheel will rest only upon the tread. The rounded or arcuate upper surface of the rib is of such configuration as to cause the wheel to engage the rib at the tread 18. In the usual wheels of railroad equipment of the United States railroads, the taper is one to twenty. The rib 16 is disposed closer to the leg 12 than the leg 13 in order that the elongate groove 22, defined by the sides 23 and 24 of the rib and the leg 13, respectively, is sufficiently wide to accommodate the flange 25 of the wheel 20.

In order that one-half of the area moment of the cross section of the rail be disposed above the tread and one-half be disposed below the tread, the legs 12 and 13 are

2

provided with outwardly extending flanges 30 and 31, which are disposed above the tread 18. One-half of the area moment of the cross section of the rail lies above the horizontal line B—B passing through the tread 18 and one-half lies below the line B—B. The rail is also so dimensioned as by making the leg 13 wider than the leg 12 so that one-half of the area moment of the cross section of the rail is disposed on one side of the vertical line A—A which passes through the tread and one-half on the other. As a result, the center of gravity of any cross section of the rail lies at the tread 18 at such cross section. The tread itself extends longitudinally at the longitudinal center of the rail.

In use, the base 11 of the rail is rigidly secured at its opposite end portions to fixed structures upon which its flat bottom surface 15 rests so that the rail is free to deflect downwardly under the load or weight imposed by any load, such as the wheel 20 as it rolls along the tread 18 of the rail. The downward deflection of the rail may be detected and measured by any suitable mechanism, such as a load cell disposed below the rail in operative engagement with the bottom surface 15 of the rail directly below the center of gravity of the rail.

Since the load upon the rail is always imposed at a point on the tread 18 which is always at the center of gravity of the cross section of the rail at such point, the downward deflection of the rail will be proportional to and caused only by the downward force of the load or weight exerted on the rail since any drag or frictional forces between the wheel and the rail will not generate any torsional forces about axes transverse to the longitudinal axis of the rails since such drag or frictional forces at any point along the rail, whenever the wheel is at any point along the rail, will act at the center of gravity of the cross section of the rail at such point. Any transversely acting forces exerted on the rail by the wheel, such as those caused by wind acting on the vehicle mounted on the wheel, will not generate any torsional forces acting about axes parallel to the longitudinal axis of the wheel since again such forces will necessarily be exerted at the center of gravity of any cross section of the rail at any point at which the wheel contacts the rail so that such forces will again not result in any vertical deflection of the rail.

It will be now apparent that a new and improved rail for use in weighing devices and the like has been illustrated and described which provides a tread for the beveled peripheral annular bearing surface of the wheel of railway vehicles, the tread being disposed at the center of gravity of any cross section of the rail.

It will further be seen that the rail includes a base having upwardly extending legs along the two side edges thereof and an upwardly extending longitudinally extending rib intermediate the legs which provides a tread or contact surface for a beveled wheel.

It will also now be seen that the rib is disposed closer to one of the legs than the other in order to provide a groove between the rib and one of the legs of proper width for accommodating the flange of the wheel.

It will further be seen that the upper ends of the legs are provided with flanges which are disposed above the tread in order to cause the center of gravity of the cross section of the rail at any point along the length thereof to be at the tread so that one-half of the area moment of the cross section of the rail is disposed above the tread and one-half is disposed below the tread.

It will further be noted that the relative dimensions of the various sections of the rail are so dimensioned that one-half of the area moment of the cross section of the rail is disposed to one side of the tread and one-half to the other side of the tread.

It will further be noted that the tread extends along a longitudinal line on the rib which is disposed midway between the outer ends of the flanges of the rail.

It will further be seen that due to the placement of the tread at the center of gravity of the rail that any vertical deflection of the rail caused by an object which is moving longitudinally across the rail is supported by the tread thereof is proportional only to the weight imposed by the object on the rail and does not vary in accordance with the drag or frictional forces between the rail and the object or any other extraneous forces exerted by the object on the rail, such as lateral forces due to wind acting on the object.

The foregoing description of the invention is explanatory only, and changes in the details of the construction illustrated may be made by those skilled in the art, within the scope of the appended claims, without departing from the spirit of the invention.

What is claimed and desired to be secured by Letters Patent is:

1. A rail including: a base; a pair of legs integral with the base and extending upwardly therefrom at the sides thereof; a rib extending upwardly from the base and providing a longitudinally extending tread, the center of gravity of any cross section of said rail being at the tread.

2. A rail including: a base; a pair of legs integral with the base and extending upwardly therefrom at the sides thereof; a rib extending upwardly from the base and providing a longitudinally extending tread, said legs having outwardly extending flanges whereby one-half of the mass of the rail is disposed above the tread and the other one-half of the mass of the rail is disposed below the tread, one-half of the area moment of the cross section being disposed to one side of the tread and the other one-half of the mass of the rail being disposed to the other side of the tread, the center of gravity of any cross section of said rail being disposed at the tread.

3. A rail including: an elongate horizontal base having integral legs extending upwardly from said base at the sides thereof; a rib extending vertically upwardly from said base between said legs and in parallel spaced rela-

tion thereto, said rib having a horizontal longitudinally extending tread for supporting a beveled wheel as it runs therealong, said legs having outwardly extending flanges disposed above said tread, the center of gravity of said rail being disposed on said tread, said rail being uniform in cross section throughout its length.

4. A rail including: an elongate horizontal base having integral legs extending upwardly from said base at the sides thereof; a rib extending vertically upwardly from said base between said legs and in parallel spaced relation thereto, said rib having a horizontal longitudinally extending tread for supporting a beveled wheel as it runs therealong, said rib being disposed parallel and spaced to the central longitudinal axis of said rail, said tread extending longitudinally centrally of said rail, said legs having outwardly extending flanges disposed above said tread, the center of gravity of said rail lying on said tread, said rail being uniform in cross section throughout its length.

5. A rail including: a base, a pair of legs integral with the base and extending upwardly therefrom at the sides thereof; a rib extending upwardly from the base and providing a longitudinally extending tread, the center of gravity of any cross section of said rail being disposed at the tread, said tread being longitudinally centrally disposed relative to said rail.

6. A rail including: a base, a pair of legs integral with the base and extending upwardly therefrom at the sides thereof; a rib extending upwardly from the base and providing a longitudinally extending tread, said legs having outwardly extending flanges whereby one-half of the area moment of the cross section of the rail is disposed above the tread and one-half is disposed below the tread, one-half of the area moment of the cross section of the rail being disposed to one side of the tread and the other one-half being disposed to the other side of the tread, the center of any cross section of said rail being disposed at the tread, said tread being longitudinally centrally disposed relative to said rail.
